UNITED STATES PATENT OFFICE.

ROCHUS MAX ZU LYNAR PASSY-DE CHIMANG, OF NEW YORK, N. Y.

AIRSHIP.

Application filed December 23, 1921. Serial No. 524,479.

To all whom it may concern:

Be it known that I, ROCHUS MAX ZU LYNAR PASSY-DE CHIMANG, a citizen of the United States, residing in the city, county, 5 and State of New York, have invented certain new and useful Improvements in Airships, of which the following is a specification.

My invention relates to lighter than air 10 aircraft and more particularly to those classed as dirigibles.

One object is to increase the carrying capacity of the dirigible without enlarging the gas bag containing portion of the same.

15 Another object of my invention is to diminish as much as possible the head resistance of an aircraft of the type by building nearly all of the outwardly projecting parts within the outline of the dirigible 20 thus presenting a smooth surface to the air.

A further object of the invention is to reduce the head resistance of a dirigible by distributing the displacement of air.

These three and other objects as will here- 25 inafter appear are accomplished by constructing an elongated dirigible which is arch shaped in section throughout its length. In this longitudinal arch shaped construction the gas containing bags occupy $\frac{2}{3}$ of 30 the arch, that is, the upper halves of the legs of the arch and the connecting portion of the same. The lower longitudinal halves of the legs are divided into cabins, supply and pilot rooms, etc., as might be considered 35 expedient.

From the drawings and from the above description it will be understood that the connecting portion of the arch forms what might be called an aeroplane wing which 40 when the dirigible is in flight and the bow of the same is elevated for ascending, will have the same effect as an aeroplane wing and thus greatly add to the lifting and carrying capacity of the dirigible without enlarging 45 the gas bag containing portion of the same. In addition to the above, the lower surface of the connecting portion is more efficient as a carrying surface, because the legs on either side of the same prevent 50 the air from moving laterally from under the surface.

As stated in the third object and as will be understood from the drawing and the description which has gone before, that it is 55 easier to force an arch shaped or a similarly shaped body through the air than a cy-

lindrical body which has the same area or volume as the arch shaped body. This is due to the fact that the displacement of the air is distributed, that is, the air is displaced by the arch shaped dirigible by a number of points or a continuous point in proportion to its area or volume, whereas, in the cylindrical form, for the same area or volume it is displaced by a single point.

This construction adds also greatly to safety of flying, for should through accident most of the gas escape from the bags, this arch shaped construction will form an air pocket and have a sort of parachute effect 70 and thus prevent a sudden drop of the dirigible.

For ascending and landing, or for controlling the height the dirigible is to fly, the same is provided with pumps, each connected with a number of tanks, which pumps when operated are adapted to draw the gas out of the gas bags of the dirigible and compress it into tanks thus reducing the buoyancy of the dirigible and causing the 80 same to descend, and for ascending of course the gas is again allowed to pass from the tanks into the gas bags.

The top surface of the arch shaped dirigible is utilized as a landing surface for 85 aeroplanes in order that the passengers and goods may be exchanged while the dirigible is in flight, therefore stairways are provided to connect the lower part of the legs of the dirigible to the top surface of the 90 same.

Referring to the drawings:

Figure 1 is a perspective of the dirigible.

Figure 2 is a fragmental perspective of 95 the skeleton framework.

Figure 3 is a fragmental longitudinal section of the forward part of the dirigible.

Figure 4 is a side elevation of the rear end of the dirigible, partly in section.

Figure 5 is a stern end elevation of the 100 dirigible.

Figure 6 is a vertical section taken through the body of the dirigible.

Figure 7 is a broken top view of the parts 105 shown in Figures 1, 3 and 4.

Referring more in detail to the drawings, numeral 1, designates in general the elongated body of the dirigible which as stated in the foregoing is arch shaped in section throughout its length.

This arch is formed by a number of sections 2 Figures 2 and 3, throughout the 110

length of the dirigible and which are of course, arch shaped. Each of these sections comprises an outer arch shaped girder 3 and smaller arch shaped girder 4. The inner girder is formed by separate girders as will be noted from the inspection of the Figure 2. It comprises two substantially vertical arranged girders 5 somewhat adjacent the legs of the outer girder 3, the upper ends 10 of which are secured to the top portion of the outer girder 3, and a horizontal girder 6 somewhat adjacent, the top part of girder 3, both ends of which connect with the legs of the same, and, where the girder 6 crosses 15 the girders 5—5 they are secured together.

The lower ends of the girders 5—5 and the adjacent leg ends of arch girder 3 are connected by beams 7—7. To reinforce the sections 2, the legs of the same are connected 20 by a girder 8. Other reinforcing girders for the sections 2 are also shown in Figure 2.

It will therefore be understood that the outer arch 3 and the inner arch 4 with beams 7—7 form a proportionally wide arch shaped 25 space as shown in Figure 6.

As stated hereinbefore a number of these sections are located along the length of the dirigible. These sections 2 Figures 1 and 2 are spaced apart and held into place by a 30 number of spaced longitudinal beams 9 which connect as shown in Figure 2 all the outer girders 3 and in a like manner all the inner girders 4 and further connect longitudinally the connecting beams 7—7.

35 In order that the dirigible will resist a torsional or twisting strain the sections 2, Figure 2, are further connected by crossed girders 10.

The Figures 1, 3, 4, and 7 show in general 40 the outline of the dirigible. The widest part of the dirigible is at 11 somewhat near the bow 12, and from this wide part the body of the dirigible tapers to a sharp edged arch bow 12 and a sharp edged arch at the 45 stern 13. The tunnel 14 formed by the arch of the dirigible is narrower at the bow and gradually widens at the stern 13. The reason for the sharp pointed bow and stern and the tapering tunnel of the dirigible is 50 of course obvious. The sharp arch shaped bow 12 is formed by the inner girder 4 and the sharp arch stern is formed by the last outer girder 3. The sections 2 between the bow and the stern, are so formed as to their 55 location in the dirigible, and likewise the girders 9.

The longitudinal arch shaped space Figures 1, 3, 4, 6, and 7 formed by sections 2 and the beams 9 may be divided into 3 main 60 longitudinal sections. The longitudinal leg portions of the arch, are designated by 15 and top longitudinal portion of the arch is designated by 16. The longitudinal sections 15 Figures 2, 3, and 6 are each divided 65 into 4 longitudinal compartments 17, 18, 19

and 20, one above the other. The compartments 17 are formed by floorings 21 immediately above the bottom of the legs and is occupied by water supply tanks, 22. The longitudinal compartments 18 are of greater 70 height than compartments 17 and are formed by the floorings 21 and floorings above designated by 23.

These longitudinal compartments 18 may be divided into kitchens, cabins, supply 75 rooms, etc., as might be considered expedient. These compartments have windows 24 on both sides of each leg of the arch and the same compartments have doors 25 on the inside of each leg of the arch.

80 The compartments 19 are of substantially the same height as the compartments 17 and are formed by the floorings 23 and floorings 26 and contain the ascending and descending means of the dirigible as will be described 85 hereinafter.

The three longitudinal compartments occupy somewhat half of the longitudinal sections 15 and the remaining spaces 20 above the floorings 26 and the top longitudinal portions 16 are occupied by gas bags 90 as designated in general by 27.

95 Stretched over the framework of the dirigible with the exception of the part occupied by longitudinal compartments 17 and 18 is the usual balloon material 28. The framework occupied by compartments 17 and 18 are covered by some material preferably duraluminum as designated by the numeral 28A in Figure 2.

100 For motive power, the dirigible, Figures 1, 3, 4, 5 and 7 is provided with engine rooms 29 mounted in the both sides of the bow 12 and the stern 13 in the ends of the longitudinal compartments 20 which at this point 105 are not occupied by gas bags 27. These rooms contain engines 30 which drive their respective propellers, 31. The propellers at the bow are tractors and those at the stern are of course pushers.

110 Located below the engine rooms in both sides of the bow are pilot rooms 32 Figure 3. These rooms have controls for moving the vertical rudder 33 and the horizontal rudders 34 which are located at the stern of the dirigible.

115 The rudder 33, Figures 1, 4, 5 and 7 of course mounted on a vertical shaft 35 which is aligned with the center line running through the dirigible and is pivoted at one end 36 to the upper edge of the stern shaped arch 13 and the lower end 37 to the connecting beam 8. This rudder is directly in line with the stream of air passing through the arch shaped space 14 thus efficient steering is attained.

120 The horizontal rudders 34 are pivoted to the rear ends of fins 38 which are mounted upon the outside of the dirigible at the stern 13. These rudders control to a small extent 125

the height at which the dirigible is to fly, whereas the change in the quantity of gas by the ascending and descending means will control larger changes in the heights.

5 Numerals 39 designates the gasoline supply rooms for the engines.

From the Figures 3 and 4 it will be understood that the top connecting portion of the arch stated hereinbefore, forms an aero-

10 plane wing which has a carrying surface 40 and an upper surface 40^A, thus it will be understood that when the dirigible is in flight and its bow is elevated, the carrying and lifting capacity is greatly increased.

15 The longitudinal spaces 16 and 20—20 Figures 3 and 6 between the sections 2 are occupied by the gas bags 27. These three spaces between the section 2 are each occupied by three separate gas bags as shown 20 in the Figure 6 and are numbered 41—41 and 42. Numerals 41—41 designate the gas bags contained in the compartments 20 and the numeral 42 designates gas bags which

occupy the top compartment 16. Each set 25 of gas bags 41—41 and 42 between the sections 2 are connected with one another by pipes 43—43 and the lower bags 41—41 are connected by pipes 44—44 to the ascending and descending means of the dirigible in 30 both of the compartments 19. These pipes 44—44 are connected with motor driven pumps 45, which are connected with tanks 46 by a pipe 47. The motor driven pumps draw the gas from the 35 bags and compress it into the tanks 46 and valves 48 in the pipes 47 will retain the gas in the tanks 46 and the consequent reduction of the buoyancy of the dirigible will allow the same to descend.

40 For ascending, the gas is again allowed to pass from the tanks into the bags by opening valves 48 of pipes 49 which connect the tanks directly with the bags.

In order to prevent jolting of the dirigible when it descends and comes to rest on the ground, a number of air cushions 50 are provided on the undersides of the legs of the arch.

45 These pumps and tanks for the sets of bags may or may not be simultaneously controlled from the pilot room. Near the bow of the dirigible a greater number of sections 2 are interposed for reinforcement, and the gas bags are therefore divided into still 50 smaller longitudinal sections. These bags of course are connected with one another so as to permit the associated pumps to draw out the gas when so desired.

55 As stated in the foregoing means are provided for the exchange of passengers and goods while the dirigible is in flight and,

for this purpose, the flat surface 40^A, Figures 1, 3, 4 and 7 is utilized as a landing place for aeroplanes and in order that passengers and goods may be transferred to 60 and from cabins or compartments 17, 18 and 19 stairway 52 is provided for connecting the landing surface with the same. The opening formed by the stairway 52 is covered by a shed 53. Mooring hooks 54 are 65 provided on the surface for securely holding the aeroplanes to the dirigible when so desired.

70 Mounted upon the surface 40^A near the stern 13 is an observation room 55 which 75 is also connected with the legs of the arch by a stairway (not shown).

The compartments 17 and 18 and the doors and windows of the compartment 18 are built water proof so that the dirigible 80 might alight upon water when desired and thus serve as pontoons. The air cushions 50, when the dirigible alights on water also act as pontoons.

85 In airship building of course, materials having the greatest strength and lightness such as dur aluminum for the sections 2 beams 9, etc., are used.

Having thus described my invention, what I claim is:

1. In an airship, the combination of an elongated rigid framework which is arch shaped in section thus forming a tunnel throughout its length, of a flat surface 95 formed by the top of the arch, a flat surface 95 formed by the underside of the arch, gas bags contained in the upper part of the framework, compartments such as pilot, supply rooms contained in the lower parts of the framework, a cotton material covering the gas bag containing portion of the framework, a rigid material covering the compartment containing portion and the framework, of motive power contained in the framework.

100 2. In an airship, the combination of a series of spaced vertically arranged arch shaped sections, of a series of spaced longitudinally arranged girders connecting the arch shaped sections thus forming an arch 105 shaped body having a tunnel extending throughout its length, gas bags contained in the arch, compartments such as pilot, supply rooms etc., contained in the arch, an envelope covering the gas bag containing portion of the arch, a rigid material covering the compartment containing portion of the arch, and motive power for the airship contained in the arch.

110 In testimony whereof I have signed my name to this specification.

ROCHUS MAX DE LYNAR PASSY-DE CHIRANG.
